FINGER RING

Norman N. Breier, Mount Oliver, Pa.

Application August 26, 1949, Serial No. 4,709

Term of patent 3½ years

(Cl. D45—10)

To all whom it may concern:

Be it known that I, Norman N. Breier, a citizen of the United States, residing at Mount Oliver, in the county of Allegheny and State of Pennsylvania, have invented a new, original and ornamental Design for a Finger Ring, of which the following is a specification, reference being had to the accompanying drawing, forming part thereof.

I claim:

The ornamental design for a finger ring, as shown.

NORMAN N. BREIER.
